The B battery supply connects to the amplification system at the terminals indicated and the A battery supply is connected to the terminals designated for supplying power to the circuit 12. It will be observed that there is absolutely no electrical connection between the negative side of the cathode 6^c of detector tube 6 and the input circuit 4-5 or the grid electrode 6^a. The input circuit connects through a lead 14 to a point of positive potential 15 adjacent the plate 6^b.

In Fig. 2 I have illustrated my invention as applied to a five tube radio receiving circuit using one stage of radio frequency amplification and plate to grid coupled detector tube embodying the principles of my invention and three stages of resistance coupled audio frequency amplification. The radio frequency amplification stage has been designated at 10 having the inductance 16 in its input circuit tuned by condenser 17, the inductance 16 being coupled with the primary coupling coil 3. The output circuit of radio frequency amplifier includes coupling coil 18, which delivers high frequency signaling energy to inductance 4 of detector tube 6 arranged as described in connection with Fig. 1. There is no electrical connection between the grid electrode 6^a and the cathode 6^c. The detector 6 delivers the rectified energy to the resistance coupled amplification system constituted by tubes 7, 8 and 9.

In Fig. 3 I have illustrated a modified arrangement of circuit for detector tubes where the connection 14 from the input circuit of the tube includes a high resistance 19 in series therewith before terminating at the point 15 in the output circuit of the electron tube system. The interposition of the resistance in the circuit serves to control the operation of the detector circuit preventing a condition of oscillation while maintaining a condition of extreme sensitivity with the desired degree of regeneration.

In Fig. 4 I have shown the detector circuit operating in conjunction with the radio frequency amplification stage 10 and the transformer coupled audio frequency amplifier constituted by electron tubes 20 and 21, having their circuits coupled with the output of the detector tube and interlinked with each other through transformer 22 and 23.

In Fig. 5 I have illustrated a modified arrangement of detector tube wherein a condenser 24 is arranged in circuit with the lead 14 in series with the input circuit and the output circuit of the electron tube 6. By varying the value of capacity 24 the operation of the detector circuit may be stabilized, the effect of the incoming signal increased and the circuit rendered extremely selective to the incoming frequency.

In Fig. 6 I have illustrated a modified circuit arrangement of my invention where connections are established between the grid and plate electrodes of an electron tube amplification system through shunting resistors. I have illustrated two stages of amplification constituted by tubes 25 and 26 having their grid and plate electrodes shunted by resistors 27 and 28. The grid electrodes of each of these tubes connects to leads 29 and 30 with resistance 31 to a point 32 adjacent the high potential B supply system.

In Fig. 7 I have illustrated a further system of control for the electron tube detector circuit where the condenser 24 in the input circuit of the tube 6 is shunted by means of a variable resistor 33. This arrangement serves to keep the detector grid 6^a out of the negative side of the B battery circuit at the same time that the efficiency of the tube system is increased.

I have described certain preferred embodiments of my invention, but I desire that it be understood that modifications may be made and that no limitations are intended except as may be imposed by the scope of the appended claims.

What I claim as new and desire to secure by Letters Patent of the United States is as follows:

1. In an electron tube system the combination of an evacuated vessel, grid, filament and plate electrodes in said vessel, input and output circuits interconnecting said electrodes in non-regenerative relation, a source of potential for heating said filament electrode, a source of potential disposed in circuit with said plate electrode for imparting a positive polarity to said plate electrode, said input circuit being substantially independent of said filament electrode with respect to oscillatory currents in said input circuit and having a connection through a resistance with said output circuit to a point adjacent said plate electrode.

2. In an electron tube system an evacuated vessel, grid, filament and plate electrodes within said vessel, a source of potential for supplying heating current to said filament electrode, a source of potential for impressing a positive charge upon said plate electrode, an input circuit connected to said grid and plate electrodes, an output circuit disposed between said plate and filament electrodes, said circuits being connected in non-regenerative relation and a composite impedance interposed in the connection between said input and output circuits and connected to a point adjacent said plate electrode.

In testimony whereof I affix my signature.
JOHN L. LUDLOW.
